[57] CLAIM

The ornamental design for a truck cab caddy, as shown and described.

DESCRIPTION

FIG. 1 is a perspective view of a truck cab caddy embodying my new design.

FIG. 2 is a front elevational view thereof on a reduced scale.

FIG. 3 is a side elevational view thereof on a reduced scale.

FIG. 4 is a top plan view thereof on a reduced scale.

FIG. 5 is a bottom plan view thereof on a reduced scale.

FIG. 6 is a rear elevational view thereof on a reduced scale.

The side of the caddy opposite that shown in FIG. 3 is a mirror image thereof.
